COLLAPSIBLE CONTAINER

Gustave A. Trost, San Francisco, Calif., assignor
to Fleishhacker Paper Box Company, San
Francisco, Calif., a corporation of California

Application May 21, 1941, Serial No. 394,489

3 Claims. (Cl. 229—41)

The present invention relates to boxes and containers such as are generally constructed of cardboard or other pliable material, and more particularly to a box or container of the type and style generally referred to as foldable, knock-down or collapsible, and in which the box or container as a whole is constructed from a single blank.

An object of the invention is to provide a box or receptacle that can be economically manufactured and that can be collapsed into a flat unit for shipment and quickly set up for use in a simple and convenient manner.

Another object of the invention is to provide a collapsible box or receptacle that may be manufactured by automatic machinery in an improved manner and with greater facility than heretofore and to these ends to provide a simple and uncomplicated blank which is adapted for such manufacture.

Another object of the invention is to provide a collapsible or folding box formed from a single blank of pliable material or cardboard and so arranged that when the parts of the box are moved to cause the box to assume its set-up condition, the tendency of said parts will be to move toward their proper positions and be retained in said condition.

Another object of the invention is to provide a collapsible box unit having outwardly folded end wall portions and an infolding bottom forming portion so constructed and related that when pressure is exerted upon said outwardly folded end wall portions, said end wall portions will assume their normal position and said infolded bottom portion will simultaneously assume its unfolded and normal position with respect thereto in a single operation.

Another object of the invention is to provide a collapsible box wherein the folded portions reinforce and rigidly stay the corners to thus provide a box which will withstand rough usage and, when filled, will not disengage at the corners, as frequently occurs with prior boxes of this type.

A further object of the invention is to provide a collapsible box of the class described in which the parts are so arranged that it can be manufactured and shipped in a collapsed or knocked down condition and finally put into a condition for use in a simple and convenient manner by the consumer without requiring any mechanical operations or other special attention.

Other objects and advantages of the invention will be in part evident to those skilled in the art

and in part pointed out hereinafter in connection with the accompanying drawing, wherein there is shown by way of illustration and not of limitation a preferred embodiment thereof.

5 In the drawing:

Figure 1 is a perspective view of a collapsible box constructed in accordance with the invention;

Figure 2 is a developed view showing the box forming blank in its flat, unfolded condition.

Figure 3 is a side view of the box as it appears when collapsed and ready for shipment to a consumer, and

Figure 4 is a view looking into the box and showing the manner in which it is extended from its collapsed condition to its fully opened and usable condition.

In the drawing the invention is shown as embodied in a box of rectangular configuration having a length that is substantially twice its width, and a depth of approximately one-half its width. This is a conventional box, such as might be used for the shipment of candies, flowers and the like, or for shoes and other wearing apparel. It is to be understood, however, that the box may take other forms. For example, it may be perfectly square and of varying depths, or it may be constructed as a square or relatively long and narrow box. While the box is here shown as having a cover forming member formed integral with the blank, it will also be understood that a separate cover may be provided, if desired. A novel feature of the box is believed to reside in the fact that all of the interlocking and intricately cut and creased portions of the blank are embodied in the end forming portions thereof. As a result of this, it is possible to provide for boxes of various lengths with the same cutting die by simply cutting the blanks with different dimensions between the end forming portions.

With reference to Figure 1 of the drawing, it will be noted that the box has a bottom portion 10 and back and front sides 11 and 12, and end walls 13 and 14. Hinged to the back wall 11 the box is also provided with a cover forming flap 15 that has a tongue 16 which is disposed inside of the front wall 12 when the box is closed. At this point it will also be noted that the end walls 13 and 14 have upstanding portions which fold inwardly to form end flaps 17 and 18 over which the cover 15 is disposed. It will also be noted that the box bottom 10 has integrally formed end portions 19 that are provided with notches 20 disposed along its medial line. As here illustrated

and as will be more particularly pointed out hereinafter, these extending end portions 19 of the box bottom 10 have diagonal folds or creases 21 which extend inwardly and upwardly from the bottom corners of the box when the end portions 19 are in their upright position. At the same time, it will be noted that the end walls 13 and 14 are formed in two parts which are carried by the back and front walls 11 and 12 of the box. These parts, which form the end walls 13 and 14, are adhesively secured together intermediate the sides of the box and at one side of a vertically extending and centrally disposed fold line 22 along which the end walls 13 and 14 are adapted to fold outwardly. Arranged in alignment with the fold lines 22 of the end walls 13 and 14 there is a further fold line 23 which extends along the longitudinal center of the box bottom 10 and upwardly into the notches 20 of the end portions 19 and along which the box bottom 10 is adapted to fold inwardly as the end walls 13 and 14 fold outwardly into their collapsed position. This simultaneous or conjoint folding action of the box bottom 10 and the end walls 13 and 14 is made possible by virtue of the diagonally disposed fold lines 21 previously described as carried by the end portions 19 of the box bottom 10, and the fact that these extending portions 19 of the box bottom 10 are glued to the end walls 13 and 14 throughout the area of the extending portions 19 located above the diagonal fold lines 21.

As is more clearly shown in Figure 2 of the drawing, the box blank is formed of a single flat sheet of material upon which all of the intricate cutting and fold creasings are provided in the end wall forming portions. As will be here seen, the end wall 13 is formed by an extending portion 24 which is carried by the back wall 11 and an extending portion 25 which is hingedly carried by the front wall 12 of the box. The extending portion 24 carries the fold line 22 and its extension beyond this fold line 22 provides for a lapped and glued connection between these parts when the box blank is assembled at the factory. Similarly, the end wall 14 is formed by an extending portion 26 at the other end of the box wall 11, and an extending portion 27 carried by this end of the front wall 12 of the box. These portions are also connected together by a lapped and glued joint, as in the case of the end wall 13. In this figure of the drawing, the extending portions 24, 25, 26 and 27 of the side walls 11 and 12 of the box are shown as shaded in that area to which the secured portions of the extending portions 19 of the box bottom 10 are glued. In this operation, it will be understood that the glue will be applied to the extending portions 19 outwardly from and above the diagonal fold lines 21 carried thereby. After the box blank has been cut, as here illustrated, and glued together, as above indicated, the blank may be collapsed into the condition illustrated in Figure 3 of the drawing by simply pressing in on the side walls 11 and 12 of the box. This will cause the box bottom 10 to fold inwardly and, at the same time, the end walls 13 and 14 will fold outwardly along the vertical fold lines 22 provided upon the extending portions 24 and 26. It will be in this condition that the box blanks will be shipped from the factory to a consumer.

When the box is received by the consumer in its collapsed condition, as illustrated in Figure 3 of the drawing, it can be rendered usable in an

instantaneous manner by merely applying pressure with the hands at the edges of the outwardly folded end walls 13 and 14, as indicated in Figure 4 of the drawing. When the collapsed box blank is subjected to pressure in this manner, the end walls 13 and 14 will be caused to assume their normal position with respect to the box bottom and, at the same time, the unglued portions of the extending portions 19 carried by the box bottom 10, here designated by the numeral 28, will flex downwardly and inwardly adjacent the diagonally disposed fold lines 21 until the box bottom 10 has assumed its flat, open position. As this occurs, the end walls will snap into their final position and retain the box in its open position. Then, after the box has been filled and the end flaps 17 and 18 have been folded inwardly, these flaps will further stiffen the end walls and prevent any collapsing thereof while the box is in use and, at the same time, the box bottom 10 will be held normal to the side and end walls of the box.

While I have, for the sake of clearness and in order to disclose the invention so that the same can be readily understood, described and illustrated specific devices and arrangements, I desire to have it understood that this invention is not limited to the specific means disclosed, but may be embodied in other ways that will suggest themselves to persons skilled in the art. It is believed that this invention is new and all such changes as come within the scope of the appended claims are to be considered as part of this invention.

Having thus described my invention, what I claim and desire to secure by Letters Patent is:

1. A collapsible box, comprising a single blank of pliable material having right-angled fold lines formed therein and defining a rectangular bottom, sides and end walls of the box, the end walls of the box being formed by two portions extending one from each side wall of the box when folded and secured together at one side of a vertical fold line disposed centrally of the box, whereby the ends of the box formed thereby may fold outwardly, said box bottom portion having bottom hinged end forming portions with centrally disposed notches extending inwardly from their outer edges and terminated short of the fold line defining the hinge of said end forming portions, diagonal fold lines formed in said end portions extending from the bottom right angled corners of the box to said notches and defining two glue areas above said diagonal fold lines that are secured one to each of said first end wall forming portions and an unglued area adjacent each of these glued areas, and a longitudinally extending score line formed centrally in said bottom portion of the box and terminating at the notches of said bottom hinged end portions along which in conjunction with said diagonal fold lines said bottom forming portion and unglued areas of said bottom hinged end portions may fold inwardly when the box is in its collapsed condition.

2. A collapsible box, comprising a single blank of pliable material having right-angled fold lines formed therein and defining a rectangular bottom, sides and end walls of the box, the end walls of the box being formed by portions extending from each side wall of the box when folded and secured together at one side of a vertical fold line located centrally of the box, whereby the ends of the box formed thereby may fold outwardly, said box bottom portion having additional end forming portions hinged to said bottom portion with

centrally disposed notches extending inwardly from their outer edges and terminating short of the fold line defining the hinge of said end forming portions, diagonal fold lines formed in said latter end portions extending from the bottom corners of the box when folded and defining glue areas above said diagonal fold lines which are secured one to each of said first end wall forming portions, a longitudinally extending score line formed centrally in said rectangular bottom portion of the box and terminating at the notches of said additional end portions and upon which in conjunction with said diagonal fold lines said bottom forming portion and the unglued part of said additional end portions may fold inwardly when the box is in its collapsed condition, and infolding flap portions defined by a fold line extending at a right-angle to the central fold line of said first end wall forming portions adapted to fold in and hold said end walls in an extended position when the box is in use.

3. A collapsible box, comprising a single blank of pliable material having right-angled fold lines formed therein and defining a rectangular bottom, sides and end walls of the box, the end walls of the box being formed by portions extending from each side wall of the box when folded and

secured together at one side of a vertical fold line disposed centrally of the box, whereby the end walls formed thereby may fold outwardly, said box bottom forming portion having extending bottom hinged ends with cut out portions forming a central notch at their outer edges which terminates short of the hinge forming fold of said bottom hinged ends and diagonal fold lines which extend outwardly from the bottom corners of the box when folded and also define partial glue areas adjacent the side walls of the box that are secured one to each of said first end wall forming portions, a longitudinally extending score line formed centrally in said bottom forming portion and terminating at the cut out portions of said extending bottom hinged end portions along which in conjunction with said diagonal fold lines said bottom forming portion and the unglued portions of said extending bottom hinged end portions may fold inwardly when the box is in its collapsed condition, foldable flaps upon the end walls of the box adapted to maintain said end walls in an extended position, and a cover forming flap upon one of said side walls adapted to overlie and hold said end flaps when the box is in use.
